Primary Examiner — Garth Rademaker*Assistant Examiner* — Aaron C Fowler(74) *Attorney, Agent, or Firm* — The Fedde Law Firm;
Kenton Fedde; Nathaniel Fedde(57) **CLAIM**

The ornamental design for a rim protector, as shown and described.

DESCRIPTION

FIG. 1 is a rear view of a rim protector, showing my new design.

FIG. 2 is a front view thereof.

FIG. 3 is a right view thereof.

FIG. 4 is a left view thereof.

FIG. 5 is a top view thereof.

FIG. 6 is a bottom view thereof.

FIG. 7 is a front top right perspective view thereof.

FIG. 8 is a rear bottom right perspective view thereof; and, FIG. 9 is a rear bottom right perspective view thereof shown in an alternate position.

The dash dot dot dash lines indicate indeterminate length and form no part of the claimed design. The appearance of any portion of the article between the dash dot dot dash lines forms no part of the claimed design.

1 Claim, 6 Drawing Sheets(56)
